DESIGN FOR A JAR FOR COSMETICS

Edith L. Imre, New York, N. Y.

Application September 19, 1939, Serial No. 87,280

Term of patent 3½ years

To all whom it may concern:

Be it known that I, Edith L. Imre, a citizen of Hungary and resident of New York city, in the county of New York and State of New York, have invented a new, original, and ornamental Design for a Jar for Cosmetics, of which the following is a specification, reference being had to the accompanying drawing, forming a part thereof:

Fig. 1 is a perspective view of a jar for cosmetics, showing my new design.

Fig. 2 is a front elevational view of the jar with the cover removed.

Fig. 3 is a front elevational view showing the cover forming a part of the design disclosed in Fig. 1 removed from the jar.

Fig. 4 is a top plan view of Fig. 2.

I claim:

The ornamental design for a jar for cosmetics, as shown.

EDITH L. IMRE.
